(57) **CLAIM**

The ornamental design for a bottle, as shown and described.

DESCRIPTION

FIG. 1 is a perspective view of a bottle showing our new design;

FIG. 2 is a front elevation view thereof, and the back, left side, and right side views being mirror images thereof;

FIG. 3 is a top plan view thereof; and,

FIG. 4 is a bottom plan view thereof.

The broken line portions are included to show unclaimed subject matter only, including the interior surface of the bottle, and form no part of the claimed design.
